UNITED STATES PATENT OFFICE.

GEORGE A. CRISMAN, OF DETROIT, MICHIGAN.

DESIGN FOR A LIGHT-FIXTURE CANOPY.

45,834.

Specification for Design.

Patented May 26, 1914.

Application filed April 4, 1914. Serial No. 829,714. Term of patent 14 years.

To all whom it may concern:

Be it known that I, GEORGE A. CRISMAN, a citizen of the United States, residing at Detroit, in the county of Wayne and State of Michigan, have invented a new, original, and ornamental Design for Light-Fixture Canopies, of which the following is a specification, reference being had to the accompanying drawing, forming a part thereof.

Figure 1 is a bottom plan view of a

canopy, showing my new design. Fig. 2 is a side elevation of the same.

I claim:—

The ornamental design for a light fixture canopy, as shown.

GEORGE A. CRISMAN.

Witnesses:

C. SAVAGE,

WILLIAM MORTON.
